Atty

UNITED STATES PATENT OFFICE.

JOHN A. HULIT, OF VILLA PARK, ILLINOIS.

TELEGRAPHIC SENDING APPARATUS.

Application filed July 12, 1926. Serial No. 121,751.

This invention relates to telegraphic sending apparatus, and more particularly to that type of sending key apparatus or instrument in which the operator moves the key sidewise 5 in one direction, to send one or more dots, and moves the key sidewise in the other direction to send one or more dashes, the key being operative to cause the transmission of successive dots as long as it is held over to one 10 side, and being operative to cause the successive transmission of dashes as long as it is held over to the other side.

The difficulty, in connection with sending apparatus of this kind, has been that split or 15 divided dots or dashes are sometimes received at the receiving station, thus making the reading of the message uncertain, as the receiving operator could not be sure whether the split or divided dot was intended to be a 20 full one, for example, and could not be certain just how to transcribe defective messages of this kind.

Generally stated, therefore, the object of 25 the invention is to provide a novel and improved construction and arrangement whereby the premature shifting of the key, from 30 right to left, or vice versa, will not result in the splitting or dividing of the dash, or in the splitting or dividing of the dot, it being 35 obvious that extra or surplus dots or dashes are more easily accounted for or understood, by the receiving operator, than are split dots or dashes, and to thus ensure more certainty in the reading or transcribing of the messages 40 at the receiving station.

It is also an object to provide certain details and features of construction and combinations tending to increase the general efficiency and the desirability of a telegraphic sending apparatus of this particular character.

To these and other useful ends, the invention consists in the matters hereinafter set forth and claimed, and shown in the accompanying drawing, in which the single figure 45 is a diagram of a telegraphic sending apparatus embodying the principles of the invention.

As thus illustrated, the sending instrument shown diagrammatically at 1 is of the kind in which the key or handle 2 is moved sidewise by the thumb of the sending operator, and when moved to the right it throws a succession of dots on to the main line, as long as the key is held in this position. As is well 55 known, the operator simply listens and hears

the correct number of dots transmitted, and then quickly releases the key, before another dot is transmitted. A skillful operator, as is well known, with a sending key of this character, can send messages very rapidly, as a 60 sidewise movement of the thumb in one direction will be sufficient for any number of dots.

The main line wires 3 extend to the receiving apparatus indicated diagrammatically at 4, and at the sending station these wires terminate, one in the armature 5, and the other in the stationary contact 6 of this relay. When the magnet 7 of this relay is energized, it pulls the armature 5 down against the contact 6, thus closing the main line circuit and 70 transmitting a dot or a dash, depending upon the length of time that the relay magnet is energized. The line circuit includes a source of current (not shown) of any suitable character, in the well known manner.

While, on the diagram shown, it is assumed that the key 2 must be pressed to the left for each dash, so that the dashes are sent manually, while the dots are sent automatically in succession, as long as the key is held to the right, it will be understood that the invention is not thus limited, as both the dots and the dashes might be transmitted in succession automatically by some other arrangement. But for the purpose of illustrating the invention it will be sufficient, as shown on the diagram, to describe a sending apparatus in which the sending key lever is held to the right to send a succession of dots, and it will be understood that the improvements shown and hereinafter described to prevent the splitting of dots, can also be used for the prevention of any splitting or dividing of the dashes as well.

When the key lever 2 is thrown over to the right and held in such position, the sending instrument 1 will cause the armature 5 to be depressed successively as many times as are necessary to send the required number of dots, a dot being transmitted over the main line 3 each time the armature 5 engages the stationary contact 6 of this relay. This is because the sending instrument closes a circuit from the battery 8 over the conductor 9 to the stationary contact 10, then through the relay armature 11, then over the conductor 12 to the magnet 7, then over the conductor 13 to the magnet 14, through the latter and over the conductors 15 and 16 to the instrument 1, and through the make and

break mechanism of this instrument to the other pole of said battery, thus intermittently energizing the magnet 7 of the sending relay. This, of course, also energizes the magnet 14, and when this relay magnet is energized, its armature 17 is pulled down into engagement with a movable contact arm 18, which latter is held normally up against a stationary contact 19 of this relay mechanism. Normally, it will be seen, there is a battery circuit from one pole of the battery through the resistance 20 and over the conductor 21 to the magnet 22, and then over the conductor 23 to the stationary contact point 19, and then through the arm 18 and over the conductors 24 and 25 to the other pole of said battery, so that the magnet 22 is normally energized; however, when the magnet 14 is energized and the arm 18 is pressed downward, the circuit of magnet 22 is opened, and its relay armature 26 is raised by a spring against the stationary contact 27, and this closes a circuit from the battery through the resistance 20 to the relay magnet 28, then over the conductor 29 to said contact 27, and then through the armature 26 and over the conductors 30 and 25 to the other pole of the battery, thereby energizing the relay magnet 28 and causing its armature 11 to be moved downward away from the stationary contact 10, and this opens the circuit of the magnets 7 and 14 previously described. When the instrument 1 opens the circuit over the conductor 16, and through the magnets 7 and 14, the apparatus is then restored to the condition shown in the diagram, and the magnet 22 remains energized until the circuit over the conductor 16 is again closed.

With this arrangement, the splitting or dividing of dots is impossible, for when a dot is once started the relays hold until the dot is completed, even though the key 2 is held over a little too long, and just long enough so that ordinarily the series of dots would terminate with a split or fractional dot. Ordinarily, with this type of sending key, the sending relay armature 5 would be released as soon as the key 2 is released, even though the key might be released just after starting a dot and before the dot was finished. With the relay arrangement shown and described, however, the dot will be transmitted, if once started, even after the key is released. It will be seen that as soon as the armature 17 touches the pivoted lever 18, and before the latter moves downward to open the magnet of the circuit 22, a circuit is formed from the battery 8 over the conductors 25 and 24, through the arm 18 and the armature 17 and the conductor 15, through the magnets 14 and 7, through the armature 11 and the contact 10, and over the conductor 9 to the other pole of the battery. Thus, momentarily, the

magnets 14 and 7 are energized over a circuit that does not pass through the sending key instrument 1, thus holding the armature 5 down against the contact 6 long enough to send the dot, before the lever 18 is moved down far enough to break the circuit through the magnet 22, and before the circuit is closed through the magnet 28, whereby this successive action of relays is necessary and inevitable before the transmission of the dot is stopped, even though the transmission circuit in the sending instrument might be opened before the dot is finished.

With the circuit arrangement shown, it will be seen that the key 2 when pressed to the left closes a circuit over the conductor 31 through the magnet 7, over the conductor 12 and through the armature 11 to the contact 10, and then over the conductor 9 to the other pole of the battery 8, thus energizing the magnet 7 to send a dash. However, this cannot be done until after the magnet 28 is de-energized, and consequently spacing between dots and dashes is insured, as well as between dots. For example, after sending a dot, a dash can then not be transmitted until the sequence of relay operations has been completed, insuring the transmission of the full dot, as previously explained, and not until after the magnet 28 has been de-energized, the de-energizing of this magnet serving not only to terminate the transmission of the dot, but also to insure a space between the dot and the following dash. Therefore, as stated, the invention not only insures against splitting of the dots, or against the splitting of impulses, but also insures spacing between dots, as well as spacing between a dot and a dash. As stated, the transmission of the dashes, with the arrangement shown, is manual, and the length of each dash is governed by the hand of the operator, as well as the spacing between dashes. But, as explained, the invention can be employed to insure against the splitting of dashes, and to insure spacing between dashes, and can be employed in connection with electrical impulses of any kind to be transmitted over a line circuit.

Thus it will be seen that instrumentalities are provided for preventing a splitting of the impulses, or any impulses sent over the line circuit, and that such instrumentalities include a so-called locking relay 14, the latter having one energizing circuit through the key 2, and having another or locking energizing circuit through its armature 17 and the movable arm 18 and the conductor 24, as previously described. Therefore, when this relay 14 is locked in energized condition, it is energized through a circuit including contacts controlled by its own armature in the manner previously explained, thereby to prevent the splitting of the impulses as described.

Without disclaiming anything, and without prejudice to any novelty disclosed, what I claim as my invention is:

1. In combination with a telegraphic sending key mechanism for transmitting impulses, a normally deenergized sending relay having a circuit controlled thereby, controlling the line circuit, having also another circuit, and auxiliary relay mechanism including a normally energized relay and operative to close said other circuit through the sending relay to prevent splitting of the impulses. 45
2. Apparatus as specified in claim 1, said auxiliary relay mechanism comprising a third relay and a fourth relay having means to cooperatively control the energizing of said other relays. 50
3. Apparatus as specified in claim 1, said auxiliary relay mechanism comprising a plurality of additional relays at least one of which is connected to be energized in series with the magnet of the sending relay. 55
4. Apparatus as specified in claim 1, including a key circuit for energizing said sending relay to transmit dashes, said key circuit including normally closed contacts of a relay of said mechanism, thereby to insure spacing between dots and dashes, as well as between dots, there being a circuit to keep said relay of said mechanism energized and said contacts thereby open until after the transmission of a dot is completed. 60
5. Apparatus as specified in claim 1, said mechanism including a relay having normally closed contacts, and including means whereby the electric magnet of said auxiliary relay is energized until after the transmission of the dot is completed, and a key circuit for energizing said sending relay to send dashes including said normally closed contacts of said auxiliary relay. 65
6. In combination with a telegraphic sending key mechanism for transmitting impulses, a sending relay controlled thereby, controlling the line circuit, and a key circuit for energizing said relay to transmit dashes, said key circuit including normally closed auxiliary relay contacts, and means including a normally energized relay for causing the energizing of said auxiliary relay to terminate the transmission of a dot, serving to insure spacing between dot and spacing between dots and dashes. 70
7. In combination with a telegraphic sending key mechanism for transmitting impulses, a normally deenergized sending relay having a circuit controlled thereby, controlling the line circuit, and instrumentalities co-operating with said relay to prevent splitting of the impulses, said instrumentalities including a relay having a first energizing circuit controlled by said sending key mechanism, and having a second energizing circuit including normally open contacts controlled by this relay itself. 75
8. A circuit arrangement as specified in claim 7, the said second energizing circuit including the energizing coil of said sending relay. 80
9. A circuit arrangement as specified in claim 7, said second energizing circuit comprising the normally closed contacts of a third relay. 85
10. A circuit arrangement as specified in claim 7, said second energizing circuit comprising the normally closed contacts of a third relay, together with relay means for controlling the energizing of said third relay. 90

Specification signed this 9th day of July, 1926.
